UNITED STATES PATENT OFFICE.

MILLARD FILLMORE WHITE, OF GLEESON STATION, TENNESSEE.

SEED-DRILL.

SPECIFICATION forming part of Letters Patent No. 399,460, dated March 12, 1889.

Application filed July 20, 1888. Serial No. 280,497. (No model.)

To all whom it may concern:

Be it known that I, MILLARD FILLMORE WHITE, a citizen of the United States, residing at Gleeson Station, in the county of Weakley and State of Tennessee, have invented a new and useful Improvement in Seed-Drills, of which the following is a specification.

The invention relates to improvements in seed-drills; and it consists in the construction and novel combination of parts hereinafter described, illustrated in the accompanying drawings, and pointed out in the claim hereto appended.

In the drawings, Figure 1 represents a central vertical longitudinal section of a planter embodying the invention. Fig. 2 represents a plan view of the same. Fig. 3 represents a side view of the machine with the facing side cut away at top to show the coaction of the tappets on the cylinder and the slide-bar with the dropping-lever.

Referring to the drawings by letter, A designates the frame of the machine composed of the side boards, *a a*, having the handles *a'* secured to their rear ends, the top connecting-board, *a²*, and the front transverse bar, *b*, to the center of which the tongue or draft-pole *B* is connected in any suitable way. The heel of the tongue projects inward beyond said bar, and has secured to it a furrow-opener blade or share, *C*, of any desired style.

D is a hollow cylinder or drum having its shaft *d* journaled in the side boards, *a*, and divided internally into two chambers, *e e'*, by the transverse partition *E*, through which the shaft *d* passes centrally.

e² e² are equidistant openings in the face of the cylinder, which openings are preferably rectangular, and are bisected by the partition *E*, so that they will discharge simultaneously from both chambers *e e'*.

F is a sliding door with dovetailed edges that slide against and are held by the corresponding edges of the entrance-opening of the cylinder, through which entrance may be had to the chambers *e e'*.

The cylinder is provided with circumferential rabbets in the outer surfaces of its end pieces, and in one of said rabbets are secured the equidistant horizontal tappets *G*, which serve a purpose hereinafter explained.

H is a hopper situated upon the transverse board *a²* and having the opening *h* near its front through said board, which forms its floor. From said opening the dropping-tube 55 inclines downward and frontward to a point closely behind the furrow-opener.

J is the feed-lever pivoted at one end upon the top board, *a²*, and having on its middle portion the projection *j*, that passes through 60 a slot, *j'*, in the front of the hopper, and is provided with an opening, *j²*.

K is a spring secured at one end to the top board and with its free end pressing upon the front edge of the lever *J* and keeping the 65 opening *j²* to the inner side of the feed-opening *h* of the hopper. The moving end of the feed-lever *J* has a downwardly-standing pin, *L*, that passes through a longitudinal slot, *l*, in the top board, *a²*, and is secured on the 70 upper edge of the slide-bar *M*, that moves in guide-brackets secured to the adjoining side board *a*, and has a depending pin or projection, *m*, that stands in the path of the tappets *G*, and is struck thereby when the cylinder 75 rotates. When the pin *m* is so struck, the slide-bar is moved forward, the feeder-lever moved outward against the action on the spring, and the opening *j²* passed over the feed-opening *h*, permitting a portion of the 80 grain with which the hopper is filled to escape down the dropping-tube.

Feeder-levers having projections provided with openings of different sizes, according to the material—such as corn, peas, or smaller 85 grain or seed desired to be planted—may be used.

The cylinder may have one chamber filled with fertilizing material which will be dropped into the furrow when the openings *e²* turn 90 downward.

When the drill-tube and hopper are used for planting, fertilizer only can be used in the cylinder; but when the same are not used one chamber of the cylinder can be filled with 95 fertilizer and the other chamber with cotton-seed, which will be fed, together with the fertilizer, through the openings *e²* into the furrows.

N is a coverer-plate having its ends inserted in brackets secured to the inner surfaces of the side boards, *a*, at the lower cor-

ners of the rear ends thereof, and O is a scraper-bar with its ends secured to the side boards and its lower beveled edge almost in contact with the cylinder. The said coverer 5 acts in the usual well-known manner. The scraper prevents earth from adhering to the periphery of the cylindrical hopper and closing and choking the openings e^2 thereof. The cylinder, besides being a planting device, acts 10 also as a roller to close the furrows when the drill is being used.

It is evident that when the hopper and dropping-tube are used the cylinder can be used both as a fertilizer-distributer and roller 15 in front of the coverer N.

Having described my invention, I claim—

The combination, with the main frame, the hopper, the dropping-tube communicating with the hopper through its bottom, the fur-

row-opener in front of said tube, the pivoted 20 lever J, having the perforated extension passing into a slot in the front of the hopper and provided with the pin L, passing through the slot l, and the slide-bar M, pivoted to the pin L, and having the depending pin m, of the 25 cylinder D, journaled upon the main frame, provided with the door F and discharge-openings e^2 , and having the tappets G in a circumferential rabbet at one of its ends, as specified.

30

In testimony that I claim the foregoing as my own I have hereto affixed my signature in presence of two witnesses.

MILLARD FILLMORE WHITE.
